UNITED STATES PATENT OFFICE.

ROBERT G. MARR AND GEORGE A. VEDDER, OF PORT RICHMOND, NEW YORK.

DETACHABLE SMOKE HOOD.

Application filed January 19, 1924. Serial No. 687,237.

To all whom it may concern:

Be it known that we, ROBERT G. MARR and GEORGE A. VEDDER, citizens of the United States, residing at Port Richmond, in the 5 county of Richmond and State of New York, have invented certain new and useful Improvements in Detachable Smoke Hoods; and we do hereby declare the following to be a full, clear, and exact description of the invention, such as will enable others skilled 10 in the art to which it appertains to make and use the same.

Our invention consists in the novel features hereinafter described, reference being 15 had to the accompanying drawings which show one embodiment of the invention selected by us for purposes of illustration, and the said invention is fully disclosed in the following description and claims.

20 The object of our invention is to provide a detachable smoke hood for fire tube steam boilers, and is particularly designed for use in connection with such steam boilers for supplying steam for operating automotive 25 vehicles, although it is applicable to other types of boilers. In the operation of boilers of this kind in automobiles, it happens in the course of time that a tube becomes defective, permitting pressure to escape. It is easily 30 possible to repair or plug defective boiler tubes where access can be had to them for that purpose, but in the ordinary construction of fire tube boilers for automobile purposes, they are usually encased in heat insulating material and the construction of the boilers is such that a very considerable 35 amount of time and labor is required to expose the boiler sufficiently to obtain access to the fire tubes and to recover it after the repairs, whether temporary or permanent, 40 have been made. Thus, for example, in the case of a defective tube, the tube can be plugged and put out of commission so as to enable the boiler to be used with the remain-

45 ing tubes in a few minutes, and in the case of a loosened fire tube, where the tube is not injured, the joint between the fire tube and the head of the boiler can be closed by a suitable expanding tool in a few minutes, 50 and both of these operations could be performed on the road if the operator of the automobile was provided with the necessary and comparatively simple appliances, but in practice it requires about half a day to remove the insulating covering and smoke 55 hood to give access to the fire tubes and re-

assemble the smoke hood and replace the heat insulating covering thereof, which is in many cases applied in the form of a plastic mass.

60 The object of our invention is to provide a boiler of this type with a detachable smoke hood held rigidly in position with respect to the boiler, when in use, and to provide it with the necessary heat insulating material, but which is provided with a removable cover substantially coextensive with the head of the boiler so that the boiler head can be readily accessible, and if desired the entire smoke hood can be removed to give 65 access to the boiler tubes for the purpose of repairing the same either temporarily or permanently. By the use of our detachable smoke hood, a boiler tube may frequently be repaired or plugged on the road within 70 a few minutes, or in the service station, without the loss of time and expense incidental to the laborious method of removing smoke 75 hood, which is now necessary.

77 In the accompanying drawings we have 80 shown more or less diagrammatically our invention applied to the vertical boiler of well known type, for purposes of illustration, the details regarding the boiler itself, its connections, and the heating burner 85 therefor, being omitted as the same form no part of our present invention.

In the said drawings,

Fig. 1 is a perspective view of a portion 90 of the chassis of an automobile provided with a steam boiler and having our improved detachable smoke hood applied thereto.

Fig. 2 is a rear elevation of the boiler and smoke hood, a portion being broken away.

Fig. 3 is a top plan view of the smoke 95 hood.

Fig. 4 is a horizontal sectional view of the same.

Fig. 5 is a detail sectional view of part of the mechanism.

Fig. 6 is a detail sectional view of the hinged door in the hood cover, and its stop.

In the accompanying drawings, 1, represents the chassis or frame of an automobile, 2, the front wheels, 3, the radiator, and 4, the vertical fire tube boiler, all of usual or any preferred construction, the boiler being provided with the usual vertical fire tubes, 5, as indicated in Fig. 2. Our improved smoke hood comprises a cylindrical double walled casing, composed of sheet metal preferably iron or steel, and composed of an

exterior cylindrical wall, 6, and an internal cylindrical wall, 7, of less vertical extent than the exterior wall, the said walls being spaced apart by suitable spacing devices, 5 indicated at 8 in Fig. 4, being preferably formed of vertical angle iron, Z-shaped in cross section as shown, and having their flanges riveted, brazed or welded to the inner and outer shells so as to form a substantially continuous annular space between the inner and outer shells which is filled with heat insulating material, indicated at 9, which may be permanently inserted between the shells, 6 and 7. The upper and lower portions of the exterior shell, 6, extends beyond the shell, 7, and the heat insulating material, 9, as clearly shown in Fig. 2, and form annular attaching flanges, 10 and 11. The exterior shell, 6, is of such diameter that the lower flange, 10, thereof will fit snugly around the upper end of the boiler, 4, as shown in Fig. 2, and is conveniently secured thereto by an annular clamp, so as to be readily detachable therefrom. In forming this clamp we prefer to employ two nearly semi-circular bands, indicated at 12—12, of iron, steel, or other suitable metal, each of which is provided adjacent to each end with an angular bracket, 13, which is preferably formed separately from the clamp member, 12, and is provided with a base portion, 14, secured to the clamp member detachably by means of machine screws. The outwardly extending portions 35 of the brackets, 13, are provided with apertures so that when the clamp members are placed around the depending flange, 10, of the outer casing of the smoke hood, the clamp members may be connected by means of bolts, 15, and nuts, 16, and when these nuts are screwed up the clamping members will form an annular clamp which will slightly compress the depending flange, 10, of the smoke hood, and hold it rigidly but detachably with respect to the boiler, 4.

The upper portion of the smoke hood is provided with a removable cover, of sheet metal, preferably iron or steel, which is so constructed as to fit tightly within the upwardly projecting flange, 11, of the outer shell, and rest upon the upper edge of the inner shell, as indicated in Fig. 2. This cover comprises an upper plate, 17, and lower plate, 18, which is preferably provided with an annular flange, 19, secured to the upper plate, 17, in any usual or desired manner, for example as indicated in the enlarged cross section, Fig. 5, in which the upper edge of the annular vertical flange, 19, is bent outwardly, as indicated at 20, and the outer edge of the top plate, 17, is bent over the outwardly extending annular portion, 20, as indicated at 21, to form a bead which rests upon the upper edge of the exterior shell, 6. The cover is provided between the plates, 17 and 18, with heat insulating material, indicated at 22, throughout its entire extent and the cover is also provided with an aperture, indicated at 23, normally closed by a hinged cover, 24, also formed of sheet metal, preferably iron or steel, and also preferably made hollow as shown in Fig. 2, and provided interiorly with heat insulating material, 25. We prefer to make the aperture, 23, rectangular in cross section and to have the inner walls, 26, of said aperture, flanged slightly from top to the bottom of the cover and to construct the door, 24, with its lateral edges inclined inwardly so as to fit this tapered aperture when the door is in closed position, as shown in Fig. 2, thus maintaining the door in closed position and also maintaining a tight joint. The cover is held in position with respect to the smoke hood by clamping members, 27—27 provided with brackets, 28, having base portions, 29, detachably secured to the clamping members by screws or bolts, 30, and nuts, 31, uniting the adjacent ends of the clamping members, 27, when the parts are in operative position, so as to clamp the upwardly projecting flange portion, 11, of the exterior shell, 6, firmly upon the lateral edges of the cover and hold it firmly in position.

In order to provide a normal outlet for the products of combustion from the smoke hood, the hood proper is provided with an aperture, preferably rectangular in cross section, indicated by dotted lines in Fig. 2, at 32, which communicates with an outlet pipe, preferably in the form of a rectangular elbow, formed of sheet metal, preferably iron or steel, and indicated at 33, discharging downwardly as shown. This elbow can be conveniently held in operative position by providing it with laterally extending vertical flanges, 34, at its inner portion, which engage vertically disposed cleats, 35, secured to the outer shell, 6, in such manner that the elbow, 33, can be placed in position by bringing the lower ends of the flanges, 34, into engagement with the upper ends of the cleats, 35, and sliding the elbow downwardly, the elbow being constructed to conform to the curvature of the exterior shell, 6. The elbow will be maintained in operative position by the clamping members 12 and 27, respectively, the clamping member, 12, supporting the elbow at the lower ends of the cleats, and the clamping member, 27, holding it firmly against upward movement.

In the use of our improved smoke hood it will be readily understood that, should it become necessary to obtain access to the boiler tubes for purposes of repair, the bolts and nuts 30—31, may be loosened to permit the removal of the clamping members, 27—27, thereby freeing the detachable cover which may be removed so as to give access to the

upper ends of all the boiler tubes. If it is desired or considered necessary to remove the hood itself, this can be readily accomplished by loosening the bolts and nuts, 5 16—15, and freeing the clamping members, 12—12, so as to permit the removal of the entire hood. After the necessary repairs are made, the hood and cover can be replaced and securely held in position by the clamp- 10 ing members as before described.

We wish it to be understood that the bracket members, which are engaged by the clamping bolts might be formed by simply bending the end portions of the clamping 15 members, 12—27, outwardly and providing them with necessary bolt holes, but we prefer to provide these clamping members with detachable brackets held in place by machine screws, as in some instances it is difficult to remove these clamping members and replace them on account of the presence of other portions of the apparatus, and by detaching the bracket members where this is 20 desirable or necessary, the clamping members can be withdrawn endwise advantageously without interfering with the surrounding portions of the apparatus. Of course where it is possible to remove the clamping members by simply lifting them 25 vertically, it is only necessary to loosen one bolt to release the cover or smoke hood, as the case may be, and permit the removal of the same.

The hinged door, 24, is provided more particularly for the purpose of enabling the operator to inspect the interior of the smoke hood and the upper ends of the boiler tubes without removing the cover and also to afford a direct upward draft where desired in 40 the preliminary getting up steam where this is desired. Of course if a defective boiler tube happened to be located with respect to this door in the cover so that it could be reached and repaired without removing the cover, this could be done, but ordinarily the door could not be used for this purpose.

It will be readily seen that by employing our improved detachable smoke hood, access can be had to the upper ends of the 50 boiler fire tubes in a few minutes without disturbing the heat insulating material and without the necessity of taking down and rebuilding a boiler hood construction of practically permanent character with the incident expense for time and labor which 55 would be required. Therefore, by the use of our improved smoke hood repairs, whether of a temporary or permanent character, can be readily made at much less expense and 60 with much less loss of time and money. Repairs can be made on the road which is a practical impossibility where it is necessary to take down and replace a smoke hood of the usual permanent character. It will also 65 be noted that the only bolts which have to

be loosened in order to permit the removal of the cover or the entire smoke hood, as the case may be, are those connecting the clamping members, which are located on the exterior of the smoke hood, where access can be 70 had to them and where they are not likely to be so affected by heat or moisture as to interfere with their being removed by ordinary simple tools when occasion requires.

In connection with the hinged door, 24, in 75 the cover, we prefer to provide means for supporting the door in open position so that it will be maintained upright and just sufficiently past the vertical position as to remain in open position, but nearly enough to 80 a balanced position so that should the operator forget to close it the jar imparted by driving the car will cause it to fall into closed position. As shown in the drawings, 85 Figs. 1, 2, 3 and 6, the door is provided with hinge leaves, 40 and 41, riveted or otherwise secured to the top, 17, of the removable cover, and to the door, 24, respectively, and we preferably provide a stop comprising an angle plate having a flange, 42, lying upon the hinge leaf, 41, and secured to the door by the same rivets or other fastenings which hold the hinge leaf in position, and having an upwardly extending flange, 43, so disposed that it will support the hinged door in 90 substantially vertical position, as indicated in dotted lines in Fig. 6, when the door is raised into open position. If the operator should forget to close the door after opening it, the ordinary vibration of the car in starting the engine will cause the door to close, and thus prevent the products of combustion from passing out through the door opening, and to insure their discharge 95 through the outlet pipe, 33.

What we claim and desire to secure by Letters Patent is:—

1. The combination with a vertical fire tube boiler and means for supporting it upon the chassis of an automobile, of a smoke 110 hood at the upper end of the boiler, provided with a lateral smoke outlet, and provided with a readily detachable and removable cover, having an area corresponding substantially to that of the head 115 of the boiler, and capable of being removed bodily from the smoke hood to give access to all of the fire tubes for repairing the boiler without disturbing the boiler and smoke hood.

2. The combination with a vertical fire tube boiler and means for supporting it upon the chassis of an automobile, of a readily detachable smoke hood provided 125 with a lateral smoke outlet, detachably connected with the upper end of the boiler, and capable of being removed bodily from the latter without disassembling the smoke hood, said smoke hood being provided with a readily detachable and removable cover,

- having an area corresponding substantially to that of the head of the boiler, and capable of being removed bodily from the smoke hood to give access to all of the fire tubes for repairing the boiler, without disturbing the boiler and smoke hood.
3. The combination with a vertical fire tube boiler and means for supporting it upon the chassis of an automobile, of a readily detachable smoke hood provided with a lateral smoke outlet, and having at one end projecting portions for frictionally engaging and fitting the head of the boiler, and at the other end projecting portions for frictionally engaging a cover, and a readily detachable cover of substantially the same area as the boiler head engaging said last mentioned projecting portions of the head, readily detachable means for securing the cover to the hood and readily detachable means for securing the hood to the boiler.
4. The combination with a vertical fire tube boiler and means for supporting it upon the chassis of an automobile, of a smoke hood secured to the upper end of the boiler, and provided with a lateral smoke outlet, said hood having its outer end provided with projecting portions to frictionally engage a detachable cover, a readily detachable cover of substantially the same area as the head of the boiler frictionally engaging and fitting the said projecting portions of the hood, whereby said cover can be bodily removed from said hood to give access to all of the boiler tubes.
5. The combination with a vertical fire tube boiler and means for supporting it upon the chassis of an automobile, of a smoke hood secured to the upper end of said boiler and comprising outer and inner metallic shells, and heat insulating material located between said shells, said hood having a lateral smoke outlet extending through said shells, a cover of substantially the area of the boiler head, formed hollow and filled with heat insulating material, the upper end of said hood and said cover being provided the one with an annular flange to engage and fit the other, and means for detachably securing the cover to the said hood.
6. A detachable smoke hood for a fire tube boiler, comprising a cylindrical body composed of outer and inner shells, spacing devices secured to and between said shells, heat insulating material located in the space between said shells, said body being provided at its lower end with an annular flange fitting the upper end of the boiler, and at its upper end with an annular cover engaging flange, and being provided with a lateral outlet for products of combustion, a cover of substantially the diameter of said cylindrical body, formed hollow and filled with heat insulating material, means for detachably securing said body to the boiler, and means for detachably securing the cover to the body.
7. A detachable smoke hood for a fire tube boiler, comprising a cylindrical body composed of outer and inner shells, spacing devices secured to and between said shells, heat insulating material located in the space between said shells, said body being provided at its lower end with an annular flange fitting the upper end of the boiler, and at its upper end with an annular cover engaging flange, and being provided with a lateral outlet for products of combustion, a cover of substantially the diameter of the outer shell, and comprising a bottom plate, a top plate, and a lateral flange portion, and filled with heat insulating material, said cover fitting within the outer shell of the main body and resting upon the upper end of the inner shell, detachable means for securing the said body to the boiler, and detachable means for securing the cover to the said body.
8. The combination with a vertical fire tube boiler and means for supporting it upon the chassis of an automobile, of a smoke hood secured to the upper end of said boiler and comprising outer and inner metallic shells, and heat insulating material located between said shells, said hood having a lateral smoke outlet extending through said shells, a cover of substantially the area of the boiler head, formed hollow and filled with heat insulating material, the upper end of said hood and said cover being provided the one with an annular flange to engage and fit the other, and an annular clamping member surrounding the engaging portions of the hood and cover for rigidly but detachably securing them together.
9. The combination with a vertical fire tube boiler and means for supporting it upon the chassis of an automobile, of a smoke hood comprising a main body consisting of a pair of spaced concentric shells provided with heat insulating material between them, the outer shell being provided at its lower end with a projecting annular flange to frictionally engage the end of the boiler, and at its upper end with a projecting annular flange to frictionally engage the cover, a cover comprising spaced top and bottom plates, and an annular flange portion connecting them, said cover being filled with heat insulating material and said annular flange portion frictionally but detachably engaging the upper flange portion of the hood, and annular clamping members surrounding the hood adjacent to its upper and lower ends for detachably clamping the hood to the boiler and the cover to the hood.
10. A detachable smoke hood for a fire tube boiler, comprising a main body consisting of a pair of spaced concentric shells,

provided with heat insulating material between them, the outer shell extending beyond the inner shell at each end of said body to form attaching flanges, one of which fits the end of the boiler, a cover comprising spaced top and bottom plates and an annular flange portion connecting them, and filled with heat insulating material, said cover fitting within the other attaching flange of the main body, detachable clamping devices engaging said attaching flanges, said cover being provided with an aperture, and a closure for said aperture, said main body being provided with a lateral outlet aperture for the products of combustion, and a discharge pipe connected to said main body and communicating with said aperture.

11. A detachable smoke hood for a fire tube boiler, comprising a main body consisting of a pair of spaced concentric shells, provided with heat insulating material between them, the outer shell extending beyond the inner shell at each end of said body to form attaching flanges, one of which fits the end of the boiler, a cover comprising spaced top and bottom plates and an annular flange portion connecting them, and filled with heat insulating material, said cover fitting within the other attaching flange of the main body, a clamping device engaging one of said attaching flanges comprising clamping bands, brackets detachably connected to said bands, and bolt and nut for connecting said brackets, and detachable connecting means for the other of said attaching flanges.

12. A detachable smoke hood for a fire tube boiler, comprising a main body consisting of a pair of spaced concentric shells, provided with heat insulating material between them, the outer shell extending be-

yond the inner shell at each end of said body to form attaching flanges, one of which fits the end of the boiler, a cover comprising spaced top and bottom plates and an annular flange portion connecting them, and filled with heat insulating material, said cover fitting within the other attaching flange of the main body, detachable clamping devices engaging said attaching flanges, said cover being provided with an aperture, and a closure for said aperture, said main body being provided with a lateral outlet aperture for the products of combustion, and a discharge pipe connected to said main body and communicating with said aperture.

13. A smoke hood for a vertical flue fire tube boiler for automobiles, having its upper end provided with an aperture, a hinged door for normally closing said aperture, and a stop for maintaining the door in substantially vertical and substantially balanced position when open, so that it will automatically close by the jarring or vibration of the hood.

14. A detachable smoke hood for a fire tube boiler, lateral portions at one end to fit upon the boiler, lateral portions at the other end to receive a readily detachable cover, provided with an aperture therein, means for detachably securing said lateral portions to the boiler and to said cover, and a hinged door for the cover aperture provided with a stop for holding it in substantially vertical and substantially balanced position when open, so that any jar or vibration of the hood will automatically close it.

In testimony whereof we affix our signatures.

ROBERT G. MARR.
GEORGE A. VEDDER.
